UNITED STATES PATENT OFFICE.

ASA A. WILCOX, OF ELMIRA, NEW YORK.

LIQUID INLET AND AIR VENT FOR TANKS.

Application filed October 30, 1924. Serial No. 746,844.

Difficulty is often experienced in rapidly filling the fuel tanks of automobiles and other kinds of tanks, as the usual filling tube or neck will not permit the unhampered escape of air from the tank, as such air is displaced by the inflowing liquid, the result being that the air must bubble through the liquid in the filling neck or tube, in order to escape. In so doing, a great deal of liquid is often blown back out of the filling tube or neck and totally wasted. It is the object of my invention however to overcome this difficulty, by the provision of an exceptionally simple and inexpensive inner tube for disposition within the usual filling neck or tube, said inner tube being constructed to permit the free escape of air from the tank as the liquid enters the latter.

With the foregoing in view, the invention resides in the novel subject matter herein-after described and claimed, the description being supplemented by the accompanying drawing.

Figure 1 is a vertical sectional view showing the invention.

Figure 2 is a side elevation of the inner tube.

Figures 3 and 4 are transverse sectional views as indicated by lines 3-3 and 4-4 of Fig. 2.

In the drawing above briefly described, the numeral 1 designates the filling tube or neck of a tank 2, which tank may be a reservoir for fuel, on an automobile, or any other kind of tank to which liquid is to be supplied and from which air must at the same time be exhausted. The outer end of the tube or neck 1 is provided with a removable cap 3. Commonly, when liquid is to be discharged into the tank 2, the cap 3 is removed and a nozzle on the end of a hose is inserted into the outer end of the neck 1, but when filling in this manner, a great deal of fuel is often wasted, for the reasons above set forth. I overcome this wastage by the provision of an inner tube 4 which extends from the outer end of the tube 1, substantially to or beyond the inner end of said tube 1. The tube 4 is provided with alternate external ribs 5 and air escape channels 6, the latter being open at both ends, so that the air from the tank may readily escape through them, as liquid is supplied to the tank through the tube 4. The inner end of this tube is preferably contracted by tapering it, as indicated at 7, and this contraction, serves to

direct the incoming liquid inwardly away from the wall of the tube 1, so that it will not interfere with proper escape of air through the channels 6.

The tube 4 is preferably formed of corrugated sheet metal which not only provides the ribs 5 and channels 6, but imparts circumferential resiliency to said tube, so that if it is made slightly larger than the internal diameter of the tube 1, and then contracted and forced into said tube 1, it will be tightly held in place by friction. The tapered inner end 7 of the tube serves to so contract said tube, as said tapered end may readily be started into the tube 1, and then, as tube 4 is forced further into said tube 1, it will be contracted, so that it will frictionally engage the filling neck or tube 1 and will thus effectively remain in place.

In contracting the inner end of the tube 4, said end may be longitudinally slit as indicated at 8 and portions of the tube adjacent the slits overlapped as disclosed at 9 in Fig. 4.

By employing the construction shown and described, or a substantial equivalent thereof, a device is provided which will be simple and inexpensive, yet will be very efficient and desirable. As excellent results have been obtained from the details disclosed, I prefer that they be followed, but within the scope of the invention as claimed, modifications may be made.

I claim:

1. A liquid inlet and air escape passage for tanks, comprising an outer tube to lead to a tank, and an inner liquid conducting tube within said outer tube, said inner tube extending from the outer end of the outer tube substantially to the inner end of the latter and having alternate external ribs and air escape channels, said ribs contacting with the inner side of the outer tube from the outer end of the inner tube to a point spaced from its inner end, said inner tube being tapered from said point to its inner end to direct the ingoing liquid inwardly away from the outer tube.

2. A liquid conducting tube adapted to be fixedly held in the filling neck of a tank, said tube having alternate external ribs and air escape grooves from end to end, said tube being formed of corrugated sheet metal to impart circumferential resiliency thereto, the inner end of said tube being tapered to facilitate insertion into a relatively small

neck and to direct ingoing liquid inwardly away from the wall of said neck, the remainder of the length of the tube being of uniform diameter for tight frictional contact with the inner side of the filling neck when said tube is tightly forced into the neck.

3. A liquid conducting tube of uniform diameter throughout the greater part of its length and adapted to be fixedly held in the filling neck of a tank, said tube being longitudinally corrugated and having circumferentially spaced longitudinal slits at its inner end, the metal between the slits being bent inwardly to impart a tapered formation to the inner end of the tube for the purpose set forth, the portions of the metal ad-

jacent said slits being disposed in overlapping relation.

4. In combination, a straight cylindrical tank filling neck, and a longitudinally corrugated circumferentially compressed inner tube within said filling neck and frictionally held therein throughout the greater part of its length by its own resiliency, the spaces between the corrugations of said tube being open at both their inner and outer ends, to permit escape of air from the tank while liquid is being discharged into said tank through the tube.

In testimony whereof I have hereunto affixed my signature.

ASA A. WILCOX.
